ELECTRIC CONTACT DEVICE, PREFERABLY
FOR RELAYSHellmuth Kuhnke, Malente-Gremsmuhlen,
Germany

Application June 15, 1950, Serial No. 168,191

Claims priority, application Germany
December 1, 1949

2 Claims. (Cl. 200—104)

1

My invention relates to electric contact devices for relays and other contactors and particularly to a contact spring assembly for such contactors.

The desire to give relays and like contact devices with multiple contacts a design of minimum space requirements has led to the choice of an exterior shape and size closely adapted to the cylindrical shape of the relay control coil. Such a design has also the advantage that it facilitates providing the base of the device with contact pins for plugging it into a socket in the manner of an amplifier tube. However, in the known relay designs, though the relay housing may be cylindrical, the assembly of the contact springs has a non-cylindrical overall shape so that the space available within the housing is only poorly utilized.

It is an object of my invention to provide a contact device for relays and other contactors, whose space requirements for a given length of the contact springs are considerably smaller than those of comparable known assemblies. More particularly, it is an object of the invention to provide a contact device or spring assembly of generally cylindrical overall shape whose axial height depends only upon the number of the contacts to be actuated and whose diameter is substantially determined by that of the appertaining relay control coil. Another object, akin to the foregoing, is to provide a relay in which the space within a cylindrical housing is virtually fully utilized and contains contact springs of larger effective length than those heretofore accommodated in relay housings of the same size.

To achieve these objects, and in accordance with my invention, I mount a plurality of part-circular or similarly arcuate contact springs in a common plane substantially perpendicular to the direction of contact actuation, one or several planes or levels of such spring groups being provided to form a set or assembly. According to another feature of the invention, the contact springs are actuated by a rod axially disposed and axially displaceable within the circular or cylindrical space surrounded by the arcuate springs, the rod being equipped with actuating members engageable with the springs for flexing them perpendicularly to the above-mentioned plane to thereby move the contact points of the springs into or out of engagement with corresponding stationary contacts. According to another feature, the movable contact springs and the likewise spring-like stationary contacts are

2

stacked upon one another with alternately inserted pieces of insulating material to form a set or unit, and the contact springs are designed so that only the movable springs are entrained by the actuating members.

These and other features of my invention are apparent from the embodiment illustrated on the drawing, in which

10 Figure 1 shows a part-sectional view of an electromagnetic relay with a contact device according to the invention, the section being taken along the plane indicated in Fig. 2 by I—I; and

15 Fig. 2 is a top view of the same relay, the appertaining housing being shown in cross section.

15 The illustrated electromagnetic relay has a control coil 1 mounted on the core 5 of a magnet structure composed of yokes 2 and 3. The appertaining armature 4 is connected with a pusher rod 6 which extends upwardly and axially

20 through a bore of core 5 and carries insulating actuating members 7, 8 and 9. When coil 1 is excited, the armature 4 is attracted toward core 5 and lifts the rod 6 so that members 7, 8, 9 actuate the movable contact springs 10 to 15 by engaging respective nose 16 or 17. Then the movable contact springs 10 to 15 are separated from respective lower stationary contact springs 20 to 25, and placed into engagement with upper stationary contact springs such as those de-

25 noted by 30, 31 and 32. The stationary contact springs do not have the projecting noses 16, 17 of the movable springs but are otherwise of similar arcuate shape. The various movable and stationary contact springs are stacked together

30 with intermediate spacers of insulating material such as those denoted by 36, 37, 38. Each of the two stacks of the illustrated embodiment is held together and rigidly secured to yoke 3 by means of a screw bolt 39. The number and arrange-

40 ment of the movable and stationary contact springs may be varied to suit the requirements of each particular application. The magnet structure of the relay may be mounted on an insulating base with connecting plugs similar

45 to the plug-type bases used for electronic tubes. A cup-shaped housing 18 covers the relay. It will be recognized that its interior cylindrical space is almost fully utilized by the magnet and the contact assembly. Preferably and as shown, the

50 exterior diameter of the set of contact springs is substantially equal to the diameter of the electromagnet to secure optimum space utilization at an optimum elastic length of the individual springs.

55 Devices according to the invention are not

limited to electromagnetic relays but are applicable in contactors for different actuation, for instance, manually operable switches.

I claim:

1. An electric contact device, comprising an electromagnet having a magnetizable core structure and a cylindrical coil concentrically disposed on said structure and having an axial center bore, said magnet having an axially movable armature member disposed at one axial side of said coil, an axially displaceable pusher rod joined with said armature and extending through said bore to the opposite side of said coil, a stack of axially aligned sets of contact springs insulated from each other and disposed on said core structure at said opposite coil side, each of said sets having two substantially flat springs of arcuate shape arranged substantially on a circle about said rod and in a common plane perpendicular to the rod axis, each spring being at one end rigidly mounted on said core structure and being movable at the other end, and each of said sets having in said plane an outer diameter substantially equal to the diameter of said electromagnet, mu-

10 15 20

tually insulated stationary contact members also mounted on said core structure and engageable with the respective other ends of said respective springs, said rod having axially spaced parts engageable with said springs for moving said springs relative to said stationary contact members when said rod is displaced by movement of said armature, whereby the overall space occupied by the device is minimized.

2. In a contact device according to claim 1, each of said contact springs having at said other end a radially and inwardly projecting nose engageable by one of said pusher-rod parts.

HELLMUTH KUHNKE.
